SHEET SEPARATING COMBING WHEEL

Frank L. Cross, Port Washington, N. Y., assignor
to Cross Paper Feeder Company, Boston, Mass.,
a corporation of Massachusetts

Application February 15, 1934, Serial No. 711,329

11 Claims. (Cl. 271—37)

The efficiency of sheet separating combing wheels of the construction that has been in practical use for many years depends to a large extent upon the operation of the combing wheels at substantially the critical speed for which they were designed. In this ordinary construction, the frictional resistance of the combing beads or rollers upon their axes is found to increase with the speed of operation and pressure of the combing wheels, which, in some cases, has the objectionable result of imparting so much of a drag upon the bank of sheets that the bank will separate in bunches, particularly in cases where the bank of sheets has this tendency for separation for any reason.

The object of the present invention is to improve the construction and operation of sheet separating combing wheels to avoid the above recited limitations, and in accomplishing this result, provision is made for ensuring a definite speed of rotation of the individual combing beads or rollers upon their axes in relation to the speed of translation and roll of the combing beads or rollers over the sheets that are operated upon.

The simplest form of mechanism for accomplishing the desired result consists of a power driven disk or pulley member mounted upon the usual supporting arm movable toward and away from a bank of sheets and driven through the usual mechanism for rapid rotation, a chain or endless series of freely journaled combing beads or rollers encircling and movable about the periphery of the power driven disk or pulley, and a pressure shoe or member relatively stationary and concentric with said disk or pulley and constantly engaging the peripheries of said beads or rollers and pressing them against the driving disk or pulley for maintaining traction. The beads or rollers travel between the driving disk or pulley and the pressure shoe and they have rolling engagement with both the disk or pulley and the shoe.

In operating this improved combing wheel structure the endless series of combing beads or rollers are tractionally driven by their engagement with the periphery of the power driven disk against which they are pressed by the concentric pressure shoe or member,—the power driven disk causing the series of rotating combing beads or rollers to advance at approximately one-half the speed of the power driven disk member. An important result of this reduced speed of advance or translation of the series of combing beads or rollers in rolling engagement with the surface of the pile of sheets operated upon, is the

avoidance of drag upon the sheets. In other words, the series of beads or rollers moving in sheet-advancing direction over the sheets are caused by the traction drive to individually rotate rearwardly of the sheet advance at approximately the speed of their advance (tractionally roll upon the sheets), so that the combing effect is obtained solely by the successive rapid pressure impulses of the beads or rollers, unimpaired by any drag or tendency of the beads or rollers to move at improper speed.

The maintenance of continual pressure upon the beads or rollers by the pressure shoe or member has the added advantage of preventing the objectionable acceleration of the speed of translation of the series of beads or rollers upon the driving disk or pulley when raised out of contact with the pile of sheets.

In order that the invention may be fully understood, it will first be described with reference to the accompanying drawing and the novelty afterwards more particularly pointed out in the annexed claims.

In said drawing

Figure 1 is a partial vertical longitudinal sectional view of a paper feeding machine illustrating the improved sheet combing mechanism;

Figure 2 is a similar view of the main parts of the same on an enlarged scale; and

Figure 3 is a detail sectional view taken on the line 3—3 of Figure 2.

In the illustrated preferred form of the invention I have embodied the principles in a modification of the well-known sheet combing wheel.

In Figure 1 of the drawing parts of a sheet feeding machine are illustrated in which 1 is a feed table supporting parts of a feathered out bank or pile of sheets indicated at 2. A suitable machine frame including the upright side brackets 3 supports upon a shaft 4 the forwardly projecting arms 5. In the forward ends of these arms 5 are mounted the hub shafts 6, suitably driven by a series of intermeshing gears (not shown) arranged along the arms 5 between the shafts 4 and 6 for rapidly driving the latter in the manner well understood in the construction and operation of the ordinary sheet combing wheels.

Mounted upon each power driven hub shaft 6 is a disk or pulley 7 which, as shown in Figure 3 of the drawing, may have a shallow peripheral recess 8 for the reception of the combing beads or rollers presently to be described.

In place of mounting the combing beads or rollers upon pins carried by the main body of the

combing wheel, as heretofore, I propose to arrange the combing beads or rollers 10 in an endless chain or series around the periphery of the power driven disk 7. These beads or rollers 10 are freely journalled upon pins indicated at 11 which also connect adjacent ends of the links 12 which form the series of beads or rollers into an endless circular chain.

The beads or rollers connected into an endless chain as described operate in the peripheral groove 8 of the power driven disk 7, completely surrounding the disk 7 and having free rolling frictional engagement therewith.

A pressure shoe or member 15 formed with a leather face 16 is freely pivoted at 17 upon a curved arm 18 pivotally mounted at 19 upon a comber supporting arm 5. An expansion spring 20 confined between a lug 21 on arm 18 and a shouldered screw 22 threaded through a bracket 23 on arm 5 maintains spring pressure upon the shoe 15. A lock nut 24 threaded upon the screw 22 engages bracket 23 and retains the screw 22 in the desired adjusted position to maintain the desired spring pressure.

The pressure shoe 15 is arc shaped to engage the series of combing beads or rollers concentrically with the traction periphery of the driving disk 7. The pressure shoe 15 is relatively stationary to the driving disk 7 and maintains traction between the disk and the combing beads or rollers 10.

25 represents a pile holding foot formed on an arm 26 pivoted upon the shaft 4 and engaged by a pair of toggle links 27 connecting arm 26 with a rock shaft 28 mounted in rock arms 29 and operated by suitable mechanism (not shown) for periodically moving the foot 25 into and out of engagement with the bank or pile of sheets. A link 30 connects the rock shaft 28 to the comber-supporting arm 5 so that upon straightening the toggle links 27 to force the foot 25 into engagement with the bank or pile, the comber-supporting arm 5 will be raised to move the comb wheel out of contact with the bank or pile. This mechanism for raising and lowering the comber wheels is usually automatically controlled by the movement of the top sheet that is moved forward by the comber's, and being well-known and forming no part of the present invention, is not further described herein.

In the operation of the improved sheet separating combing devices it will be understood that the disk 7 is rapidly rotated in the direction of the arrow by the usual mechanism employed for driving the ordinary combing wheels. As the disk 7 rotates anti-clockwise its periphery upon which the chain of combing beads or rollers 10 is supported tractionally engages said beads or rollers and causes them to individually and definitely rotate in a clockwise direction. The pressure shoe or member 15 is in spring engagement with the combing beads or rollers to maintain traction engagement with driving disk 7 with the result that as the beads or rollers rotate upon their individual axes and pass between the driving disk 7 and the shoe 15, the series of rotating combing beads or rollers will gradually advance or be translated in an anti-clockwise direction at approximately one-half the peripheral speed of rotation of the power driven disk 7. It will also be observed that the speed of the advance or translation of the series of beads or rollers will have a uniform definite relation to the speed of rotation of the individual beads or rollers,—irrespective of the speed of the driving disk or

5 pulley,—with the result that each combing bead or roller, upon reaching the bank or pile of sheets that is being operated upon, will roll over the surface of the top sheet without drag or forward push so that the combing effect will be due solely to the rapid succession of pressure impulses of the beads or rollers upon the pile or bank.

I claim:—

1. In a sheet separating combing mechanism, the combination with a rotary sheet combing element, of means for moving said element into and out of engagement with sheets to be separated, and means for simultaneously imparting related motions of translation and backward rotation to said combing element.

10 2. In a sheet separating combing mechanism, the combination with a connected series of rotary sheet combing elements, of means for moving said series of elements bodily toward and away from sheets to be separated, and means for simultaneously imparting opposite motions of 20 translation and rotation of related speeds to said combing elements in engagement with sheets.

15 3. In a sheet separating combing mechanism, the combination of a supporting member movable into and out of sheet combing position, and a positively operated driving member mounted upon said supporting member, with a chain of rotatable combing beads or rollers progressively supported upon and driven by said driving member, said beads or rollers being caused to advance and roll over the engaged sheets without drag or forward push.

25 4. In a sheet separating combing mechanism, the combination of a support for sheets, and a 35 comber supporting member, with a rotary driving disk or pulley, mounted upon said supporting member, an endless chain of rotatable combing beads or rollers encircling said disk or pulley and driven thereby to impart positive related 40 motions of rotation and translation thereto, said beads or rollers advancing and rolling over the engaged sheets without drag or forward push.

45 5. In a sheet separating combing mechanism, the combination of a driving surface, and a pressure surface spaced from said driving surface, with a series of combing beads or rollers supported to pass between said driving and pressure surfaces into and out of combing engagement with sheets to be separated.

50 6. In a sheet separating combing mechanism, the combination of a driving surface and a pressure surface spaced from said driving surface, with an endless series of rotatable combing beads or rollers supported and driven by said driving surface to pass between said driving and pressure surfaces into and out of active engagement with sheets to be separated.

55 7. In a sheet separating combing mechanism, the combination of a driving surface, and a pressure surface spaced from said driving surface, with an endless chain of rotating combing beads or rollers supported upon and driven by said driving surface to pass between said driving and pressure surfaces into and out of combing relation to a bank of sheets.

60 8. In a sheet separating combing mechanism, the combination of a supporting member movable into and out of sheet combing position, of the spaced relatively movable driving and pressure surfaces mounted in operative relation upon said supporting member, and an endless series of combing beads or rollers supported to operate 70 between said driving and pressure surfaces.

9. In a sheet separating combing mechanism, the combination with a supporting arm, a power driven disk or pulley journalled upon said arm, a pressure shoe movably mounted upon said supporting arm in spaced relation to said disk or pulley, and an endless series of combing beads or rollers supported upon the periphery of said disk or pulley and operating in engagement with said pressure shoe. 5
10. 10. In a sheet separating combing mechanism, the combination with a supporting arm, a power driven disk or pulley journalled upon said arm, a pressure shoe movably mounted upon said supporting arm in spaced relation to said disk 10
- or pulley, a spring device acting upon said pressure shoe, and an endless chain of combing beads or rollers movably supported upon the periphery of said disk or pulley and operating in engagement with said pressure shoe.
11. In a sheet separating combing mechanism, the combination with a support for sheets, and a comber supporting member movable toward and away from said support, with a rotary series of sheet combing elements operatively mounted upon said supporting member, and means for rolling said combing elements over the engaged sheets without drag or forward push. 10
